KNITTING MACHINE COMPANY, OF PAWTUCKET, RHODE ISLAND, A CORPORA-
TION OF RHODE ISLAND.

NEELDE-CONTROLLING MECHANISM FOR KNITTING MACHINES.

Application filed March 13, 1919. Serial No. 282,409.

To all whom it may concern:

Be it known that I, MAX C. MILLER, a citizen of Germany, residing at Cumberland Hill, in the county of Cumberland and State 5 of Rhode Island, have invented certain new and useful Improvements in Needle-Controlling Mechanism for Knitting Machines; and I do hereby declare the following to be a full, clear, and exact description of the invention such as will enable others skilled in 10 the art to which it appertains to make and use the same.

The invention relates to mechanism for controlling the operation of the needles of 15 a knitting machine in the production of tuck stitches, or of fancy or open-work fabric, during any part or parts of the knit fabric.

The invention contemplates controlling 20 the operation of the needles by needle advancing jacks, or other needle moving elements, which are normally inactive, and which may be rendered active by one or more series of deflectors arranged back of 25 the jacks and successively operated to press the jacks into active relation to the jack actuator by means such, for instance, as a cam or cams which acts progressively along the deflectors by reason of the relative travel 30 between the deflectors and cam. By providing means for throwing the deflector actuating means into and out of action during the knitting, the character of the fabric may be varied at different points. By providing 35 a plurality of series of deflectors for pressing forward different series of jacks distributed among the entire series, and also a corresponding series of deflector actuating cams, any series or combination of two or 40 more series may be rendered active during any desired part or parts of the knitting, and a wide variation in the character of fabric produced may be secured if desired.

The preferred form of the invention is 45 illustrated in the accompanying drawings embodied in a circular knitting machine. In the drawings, Figure 1 is a sectional elevation on line 1—1, Fig. 2; Fig. 2 is a sectional plan view on line 2—2, Fig. 1; Fig. 3 50 is a diagrammatic view indicating the stitch cams and jack operating cams; Fig. 4 is a detail elevation looking toward the right in Fig. 2; and Fig. 5 is a detail sectional

view showing a jack in engagement with the jack operating cam. 55

In the drawings the invention is shown as applied to a circular latch needle machine of the type used for knitting seamless hosiery. As shown, the needle cylinder 1 of the machine is provided at its lower end with a 60 gear 2 through which rotary and reciprocatory motion may be transmitted to the cylinder. The cylinder is provided with the usual vertical grooves in which the latch needles 3 are mounted. The cams for forming the knitting waves in the needles are indicated in Fig. 3, and comprise the rotary stitch cam 4, which is active during both rotary and reciprocatory knitting, the heel stitch cam 5 which is active only during reciprocatory knitting, the needle raising side cams 6 and 7, the upper center cam 8, and the lower center cam 9. After passing the stitch cams the needles are raised to the tuck level by the side cams, and are normally supported at this level by the tuck ring 10 in which the side and lower center cams are formed or mounted. The machine may also be provided with the usual cams and pickers for actuating the needles to knit 65 70 75 80 85 90 95 100 105 seamless hosiery.

In addition to the devices and mechanisms for actuating and controlling the needles to knit plain fabric, the machine is provided with needle controlling mechanism which adapts it to knit various designs of fancy or open-work fabric at any desired parts of the stocking, or to tuck upon any desired needles during any course or courses of the knitting. As shown, this mechanism includes a series of jacks 11 mounted in the needle grooves below the needles, and a jack actuating cam 12 arranged to actuate any of the jacks which may be pressed outward into position to ride over the cam. The means for pressing forward the jacks comprises one or more series of jack deflectors, preferably in the form of radially sliding pins 13, which are arranged to act on the backs of the jacks, or on the backs of a series of jacks distributed among the entire series. In the construction shown there are seven series of pins, and they are mounted in seven series of pin holes formed in the needle supporting cylinder, one above the other, as indicated in Fig. 1. The pins are differently

distributed in the different series of pin holes, and a separate actuator in the form of a cam 14 is preferably provided for forcing forward each series of pins as they travel 5 over the cam. Means is provided for throwing each cam 14 into or out of action, so that any series of pins, or any combinations of different series, may be actuated to press forward the corresponding jacks during the 10 rotation of the needle cylinder. As shown, the cams 14 are formed on a series of levers 15 which are pivotally mounted, one above the other, in a supporting ring 16 arranged within the needle cylinder. The ring fits 15 within the lower end of the needle cylinder, and is supported and held in position by a series of screws 17, the inner ends of which are arranged to overlie a ledge 18 on the cylinder. The cams are formed on the outer 20 sides of the levers, and are arranged one above the other so that they act to force forward the deflecting pins at the same point with relation to the jack cam. The cam levers are provided on their rear side with 25 a series of cam lugs 20 arranged to be engaged by a series of vertically sliding rods 21 which are guided in a fixed bracket 22 and rest on the horizontal arms of a series of bell crank levers 23. The vertical arms 30 of the bell crank levers are engaged by a series of rods 24, which may be actuated manually or by any suitable pattern mechanism to automatically control the throwing in and out of the cam levers 15 during the knitting. 35 The jacks normally lie within the grooves of the needle cylinder, so that their lower ends are out of active relation to the jack actuating cam, as indicated in full lines in Fig. 1. The cams 14 are arranged to advance the 40 pins 13 and force the lower ends of the corresponding jacks outward just before the jacks reach the jack actuating cam, as indicated in Fig. 2. The lower ends of the jacks which are thus forced outward ride up the 45 cam 12, and are retained in engagement with the cam by a rib 25 on the inner edge of the cam, which is adapted to engage a notch in the lower end of each jack. After each jack has passed off of the upper end of the cam, 50 it is pressed back into inactive position within the groove of the needle cylinder by a cam 26 arranged beyond the upper end of the jack cam in position to engage the projecting lower end or butt of the jack. 55 Whenever the jacks are to be rendered active, the heel stitch cam 5 and that part of the lower center cam 9 which lies above the tuck level of the needle butts, are withdrawn from the path of the needle butts, so 60 that the heel stitch cam 5 will no longer act to raise the needles from the tuck to the clear level. With the stitch cams thus adjusted, the only needle which will be raised to the clear level, so that they will knit and 65 cast off their loops in passing under the

stitch cam 4, will be the needles corresponding to the jacks which are pressed outward and which ride up the jack cam 12. The other needles will continue at the tuck level, as indicated by the dotted line passing across 70 the face of the stitch cam 5 in Fig. 3, and will pass down under the stitch cam 4, without casting off the previous loop. The needles will thus be controlled to knit on the needles corresponding to the active jacks, 75 and to tuck on the remaining needles. As the needles raised by the active jacks pass under the stitch cam 4, the jacks will be depressed to their normal position, as indicated in Fig. 1, by the downward movement 80 of the needles, and will remain in this position until again pressed outward into active relation to the jack actuating cam. By properly distributing the pins in the different 85 series, any desired effect may be secured in the knitted fabric.

While the invention has been shown and described as applied to a circular latch needle machine, in which the travel of the needles and jacks over the actuating cams is secured by rotation of the needle cylinder, it 90 will be understood that the invention is not confined in its application to such machine, and is applicable to other types of machines, such as dial or straight-bar machines. It 95 will also be understood that the invention may be embodied in a construction in which the needle moving elements pressed forward into active relation to the actuating cam are 100 not strictly speaking jacks, but are rather a permanently connected or integral part of the needle, such for instance as the part on which the projecting butt is formed, through which the needle may be moved in a manner similar to that given to it by a disconnected jack. It will also be understood that the invention may be utilized for raising any selected needles at any point for purposes 105 other than for tucking.

What is claimed is:—

1. A knitting machine having, in combination, a series of needles, a series of needle advancing jacks arranged to act on needles distributed among the needle series, a corresponding series of deflectors arranged to act on the jacks, means for progressively actuating the series of deflectors and the series of jacks deflected thereby during the knitting of successive courses.
2. A knitting machine having, in combination, a series of needles, a series of needle advancing jacks distributed among the needle series, a corresponding series of deflectors arranged to act on the jacks, means movable into and out of action during the knitting for progressively actuating the deflectors during the knitting of any number of courses, and means for progressively actuating the deflected jacks during the knitting of such courses.

3. A knitting machine, having, in combination, a series of needles, a series of needle advancing jacks, a plurality of series of deflectors arranged to act on different series of jacks distributed among the entire series, means for actuating any selected one or more of the different series of deflectors during the knitting of a course, and means for actuating the jacks deflected thereby 10 during the knitting of such course.

4. A knitting machine having, in combination, a series of needles, a series of needle advancing jacks, a plurality of series of deflectors for different series of jacks distributed among the entire series of jacks, a deflector advancing cam for each series over which the deflectors of that series travel during the knitting of each course while the cam is active, and a jack cam over which the 20 deflected jacks travel.

5. A knitting machine, having, in combination, a series of needles, a series of needle advancing jacks, a plurality of series of deflectors back of different series of jacks distributed among the entire series of jacks, a deflector advancing cam for each series, a jack cam for actuating the deflected jacks, and means for rendering any selected one or more of the deflector cams active during the knitting of a course.

6. A knitting machine, having, in combination, a series of needles, a series of needle advancing jacks, a series of sliding pins mounted back of the jacks, a cam over 35 which the pins travel, and a jack cam arranged to act on the jacks deflected by the advance of the pins.

7. A knitting machine, having, in combination, a series of needles, a series of needle advancing jacks, several series of sliding pins mounted back of different series of jacks distributed among the entire series, a series of cams corresponding to the different 40 series of pins arranged to advance each series at the same point, and a jack cam arranged to be engaged by the jacks deflected by the advance of the pins.

8. A knitting machine, having, in combination, a needle support provided with 50 needle grooves, needle moving elements in the grooves, a series of deflectors mounted in the support back of the elements, means for progressively actuating the deflectors to press the elements forward in their grooves, and a cam arranged to progressively actuate only those elements which are pressed forward by the deflectors.

9. A knitting machine, having, in combination, a needle support provided with 60 needle grooves, needle moving elements in the grooves, a plurality of series of deflectors mounted in the support back of different series of elements distributed among the whole series, means for selectively actuating each series of deflectors to press the corre-

sponding elements forward in their grooves, and a cam arranged to progressively actuate only those elements which are pressed forward by the deflectors.

10. A knitting machine, having, in combination, a needle cylinder provided with needle grooves, needle moving elements in the grooves, a series of radially sliding pins back of the elements, a cam arranged to act on the inner ends of the pins, and a cam 70 outside the needle cylinder arranged to actuate the elements pressed forward by the pins.

11. A knitting machine having, in combination, a series of needles, a stitch cam, a 80 series of normally inactive needle moving elements distributed among the needle series, deflectors arranged back of the elements, a cam arranged to act progressively along the deflectors by reason of the relative travel between the cams and the needles, elements and deflectors, a cam for actuating the deflected elements to clear the corresponding needles, and means for rendering the deflector cam active or inactive.

12. A knitting machine, having, in combination, a needle cylinder provided with needle grooves, needle moving elements in the grooves, a stitch cam, a side cam for raising the needles to the tuck level, normally 90 inactive needle moving elements distributed among the needle grooves, a cam fixed with relation to the stitch cam for actuating the elements to clear the corresponding needles, a series of deflectors for deflecting the elements into the path of the cam, and a cam 100 for actuating the deflectors.

13. A knitting machine having, in combination, a series of needles, a series of needle moving elements distributed among 105 the needle series, a corresponding series of deflectors for the elements, means for progressively actuating the deflectors and the deflected elements and for returning the deflectors and elements to initial position 110 during the knitting of a course.

14. A knitting machine having, in combination, a series of needles, a series of needle advancing jacks distributed among the needle series, a corresponding series of 115 deflectors arranged to act on the jacks, means for progressively advancing the deflectors to deflect the jacks and for progressively advancing the deflected jacks and for returning the deflectors and jacks to initial position during the knitting of a course.

15. A knitting machine having, in combination, a series of needles, a stitch cam, a 125 clearing cam for cooperating therewith to form a knitting wave and movable into inactive position, a series of normally inactive needle moving elements distributed among the needle series, a series of deflectors for the elements, means for progressively actuating the deflectors when the clearing cam 130

is out of active position, and means for progressively actuating the elements deflected by the deflectors to clear the corresponding needles preparatory to their depression by 5 the stitch cam.

16. A knitting machine having, in combination, a needle cylinder provided with needle grooves, needles mounted in the grooves; a stitch cam, a clearing cam for co- 10 operating therewith to form a knitting wave

and movable into inactive position, normally inactive jacks distributed among the needle grooves, a cam for actuating the jacks to advance the corresponding needles, a series of deflectors for deflecting the jacks into 15 the path of the cam, and a cam movable into and out of active position for actuating the deflectors.

MAX C. MILLER.
